WRINGER RELEASE

Thomas R. Smith, Newton, Iowa, assignor to The Maytag Company, Newton, Iowa, a corporation of Delaware

Application April 3, 1940, Serial No. 327,664

5 Claims. (Cl. 68—263)

The present invention relates to a wringer for washing machines and more particularly to a novel safety release whereby the tension and pressure between the wringer rolls may be instantaneously relieved by the operator and the rolls simultaneously separated. In the novel disclosed construction, the safety release is so positioned and arranged as to make it equally accessible from either side of the wringer and requires but little effort on the part of the operator for tripping the release and separating the rolls.

The invention further comprehends a novel wringer release for a wringer of the split type in which the upper section carrying the upper roll is pivotally mounted upon a lower section or main frame carrying the lower or driving roll, these rolls being maintained under pressure during operation, but instantaneously separated when an emergency arises.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawings, and while I have shown therein a preferred embodiment, it is to be understood that the same is susceptible of modification and change, and comprehends other details, arrangements of parts, features and constructions without departing from the spirit of the invention.

In the drawings:

Fig. 1 is a view in side elevation of the novel wringer construction.

Fig. 2 is an enlarged fragmentary view in vertical cross section taken on the line 2—2 of Fig. 5, and showing the wringer in operative position.

Fig. 3 is an enlarged fragmentary view in end elevation with parts broken away to more clearly show the details of the tripping mechanism and with the release lever tripped to release the tension and pressure on the rolls and allow for their separation.

Fig. 4 is a view in horizontal cross section of the wringer assembly and release mechanism taken on the irregular line 4—4 of Fig. 5.

Fig. 5 is a fragmentary view, part in side elevation and part in vertical cross section, of the wringer frame construction and release mechanism.

Fig. 6 is a view in perspective of the novel release lever.

Fig. 7 is a view in perspective of the tension reset handle.

Fig. 8 is a view in vertical cross section through the assembled release lever and tension reset handle taken on the line 8—8 of Fig. 4.

Referring more particularly to the disclosure in the drawings, the novel invention is shown as embodied in a wringer 1 of the split type, the operation of which is controlled through suitable gearing enclosed within a gear case 2 and a single handle 3 for controlling the starting, stopping and rotation of the rolls 4 and 5 in either direction of their travel.

The wringer 1 comprises a main frame 6 carrying the lower roll 5, and an upper frame section carrying the upper roll 4 having the opposite ends of its shaft 7 rotatably mounted in ball bearings 8 carried in the opposite wringer hinge caps 9 and 10. Each of these hinge caps is pivotally mounted at 11 to the upper end of the lugs 12 which are shown as connected to the upper ends of hinge bolts 13 located at the opposite ends and at one side of the main frame 6. At the other side of the wringer frame are located 25 a pair of hook members 14 connected to the upper ends of bolts 15, one adjacent each end of the main frame. Each of the hinge and hook bolts 13 and 15 are shown as equipped with a tension spring 16 seating at one end against the 30 underside of the shoulders 17 and 18, and at their other end against the adjustable nut 19. Each spring is thus held under compression, the amount of which may be adjusted by the adjustment of the nut 19.

35 In this form of the invention, the hinge bolts 13 are held down against the upper surface of the shoulders 17 by means of the springs which exert their pressure upon the ends of the hinge caps 9 and 10 through the tension bolts. If desired, the hinge bolts 13 may be dispensed with and the lugs 12 formed integral with the upper surface of the shoulders 17 on the main frame 6.

The handle for the tension reset comprises a cap 20 having oppositely projecting trunnions 21 each provided with spaced bearing surfaces journalled or pivotally mounted in the opposite side walls 22 and 23 of the hinge caps 9 and 10 and an intermediate flat portion 24 adapted to engage under the hooks 14 and force the hinge caps downwardly, thereby forcing the upper roll 4 downwardly against the bottom roll 5 and causing the springs 16 to exert their tension and apply pressure between the top and bottom rolls 55 of the wringer. From an examination of Figs. 2

and 3 of the drawings, it will be evident that if this reset cap 20 is turned further (see Fig. 3) than the normal or operative position shown in Fig. 2, the flat portions 24 of the trunnions 21 will disengage from under the hook bolts and thereby release the pressure on the rolls exerted by the tension springs 16. This is accomplished through a release lever 25 projecting through and above the reset handle or cap 20.

To hold the wringer in tension and to prevent the reset handle from going on past the position shown in Fig. 2, the release lever 25 is pinned at 26 to the reset handle or cap 20 in such manner that the projections or prongs 27 at the ends of the release lever stop or prevent this reset handle from moving past the normal operative position by the projections or prongs 27 abutting against the stop pins 28 secured in the inner walls 23 of the hinge caps, and in which position the tension springs 16 apply pressure to the rolls. However, when pressure is applied from either side of the wringer to the portion of the release lever 25 which protrudes through the reset handle, the projections or prongs 27 will swing away from the stop pins 28, thereby allowing the reset handle to go past the tension positions, releasing the hook bolts 15 from engagement with the flat portions 24 on the trunnions 21 and releasing the pressure on the rolls. A bracket 29 acts as a stop for the release lever by reason of its end 30 projecting into an opening or slot 31 in a side wall of the release lever and thereby limiting this lever in its upper and lower positions of movement to approximately the width of the opening or slot. In order to hold the release lever in the upper or tension position, as shown in Figs. 2 and 8, until the operator trips or depresses this lever, a spring 32 is provided between the stop bracket 29 and the upper edge of opening 31 in the release lever which tensionally maintains the reset lever in its raised position. Both the spring and stop member are shown as secured in position by means of screws or other attaching means 33.

Having thus disclosed the invention, I claim:

1. In a wringer construction, a main frame carrying a roll, an upper frame section carrying a roll and including a reset handle and a hinge cap at each end pivotally mounted on the main frame at one side thereof and in such manner that the rolls may be widely separated or moved into engagement for operation, hook bolts carried by the main frame upon the side opposite to the pivotal mounting, tension springs associated with the hook bolts and adapted to be placed under compression when the rolls are operatively engaged and to apply pressure to the rolls, trunnions carried by the reset handle for pivotally mounting the handle in the hinge cap, cam surfaces provided on said trunnions adapted to engage under the hook bolts so as to force the hinge caps downwardly, compress the springs and place the rolls under pressure, and a release lever journaled in the reset handle and projecting therethrough and thereabove to make it equally accessible from either side of the wringer for retaining the engagement of the cam surfaces and hook bolts until the operator applies pressure to the release lever and thereby releases the operative engagement between the hinge cap and hook bolts to relieve the pressure on the rolls.

2. In a wringer of the split frame type having an upper and lower section each carrying a roll and in which the lower frame section is maintained stationary and the upper frame section is

pivotedly mounted on the lower section at one side thereof, means for detachably connecting the upper frame section to the other side of said lower section and to operatively engage the rolls and maintain them under pressure, said means including spring-pressed hook bolts mounted in the lower section, a reset handle on the upper section provided with trunnions having a part adapted to be engaged under each hook bolt to tensionally retain the upper section onto the lower section and apply pressure to the rolls, and means for quickly releasing the trunnions from their engagement and relieving the pressure on the rolls, said last mentioned means comprising a release lever carried in the reset handle and projecting thereabove so as to be equally accessible from either side of the wringer, and a projection on said lever and an abutment on the upper section adapted to retain the trunnions in engagement with the hook bolts until the release lever is tripped.

3. In a wringer of the split frame type having an upper and a lower section each carrying a roll and with the upper section pivotally mounted on the lower section in such manner that the upper section may be swung open and the rolls widely separated, means for tensionally latching the upper section to the lower section and applying pressure to the rolls and comprising a pair of spring-actuated hook bolts carried in the opposite ends of the lower section and a pivotally mounted cap and reset handle having trunnions disposed at the opposite ends of the upper section, a latch provided on each trunnion and adapted to engage under the hook of said bolts whereby to compress the springs, means for retaining said trunnions and hooks latched, and a release lever projecting through the cap and so disposed as to be equally accessible and readily tripped from either side of the wringer whereupon the trunnions are disengaged from said hooks to instantaneously relieve pressure on the rolls and allow for the wide separation of the rolls and frame sections.

4. In a wringer of the split frame type having an upper and a lower section each carrying a roll and with the upper section pivotally mounted on the lower section in such manner that the upper section may be swung open and the rolls widely separated, means for tensionally latching the upper section to the lower section and applying pressure to the rolls and comprising a pair of spring-actuated hook bolts carried in the opposite ends of the lower section and a pivotally mounted cap and reset handle having trunnions disposed at the opposite ends of the upper section, a latch provided on each trunnion and adapted to engage under the hook of said bolts whereby to compress the springs, a release lever pivotally mounted in the cap and projecting thereabove so as to be equally accessible and readily tripped from either side of the wringer, a projection depending from the release lever and a stop pin provided on the upper section in the path of said projection whereby, when the projection engages the stop pin, the trunnions are held in latched position during operation and until pressure is applied by the operator to the release lever whereupon the projection swings out of the path of the stop pin and the trunnions are disengaged from said hooks to instantaneously relieve pressure on the rolls and allow for the wide separation of the rolls and frame sections.

5. In a wringer of the split frame type having an upper and a lower section each carrying

a roll and with the upper section pivotally mounted on the lower section in such manner that the upper section may be swung open and the rolls widely separated, means for latching the upper section to the lower section and including a cap overlying the upper roll and pivotally mounted in the upper section providing a reset handle for placing the rolls under pressure for the wringing operation, and means for instantaneously unlatching said sections and re- 10

lieving the pressure on the rolls, said means including a release lever pivotally mounted in the cap and projecting therethrough, a projection depending from said lever; and a stop located in the path of said projection, said projection and stop, when engaged, maintaining said sections latched until pressure is applied to the release lever to cause the projection to ride over the stop.

THOMAS R. SMITH.
